United States Patent

Des. 234,517
Patented Mar. 18, 1975

234,517

FAN

Bern M. Bonifant, Tacoma, Wash., assignor to Flex-A-Lite Corporation, Tacoma, Wash.

Filed Sept. 7, 1973, Ser. No. 395,278

Term of patent 14 years

Int. Cl. D23—04

U.S. Cl. D23—165

FIG. 1

FIG. 2

FIG. 3

FIG. 4

FIG. 1 is a front view of a fan showing my new design;
 FIG. 2 is an elevation view looking at one end edge
 of the fan;

FIG. 3 is a rear view of the fan; and,
 FIG. 4 is an elevation view looking between two adjacent blades of the fan.

I claim:

The ornamental design of a fan, substantially as shown.
